ATTORNEY.

UNITED STATES PATENT OFFICE.

EGERTON A. BLISS, OF JERSEY CITY HEIGHTS, NEW JERSEY.

DESIGN FOR A LACE-PIN.

SPECIFICATION forming part of Design No. 11,692, dated March 23, 1880.

Application filed January 30, 1880. Term of patent 3½ years.

To all whom it may concern:

Be it known that I, EGERTON A. BLISS, of Jersey City Heights, in the county of Hudson, State of New Jersey, have invented a new and original Design for Lady's Lace-Pin, of which the following is a full, clear, and exact description, reference being had to the accompanying drawing, making part of this specification, which fully shows the nature of my invention.

The object of this invention is to produce a design for lace-pins; and it consists in a lace-pin composed of crossed rifles, from which is centrally suspended by chains a target, military cap, or similar article.

A A in the drawing represent two rifles crossed; B, a target, military cap, or other article; and C C, the chains by which the target or other article is suspended below the intersection of the rifles, the chains being attached to the trigger-guards symmetrically

to the center line of the lace-pin in such a manner that the target or other article is retained centrally in relation to the crossed rifles.

The above-described design gives a neat, 25 light, and ornamental appearance to the article.

Having thus described my invention, I claim as new and desire to secure by Letters Patent—

The design for a lace-pin composed of crossed rifles A A, target, military cap, or other article B, and suspending-chains C C, as described, and shown in the accompanying drawing.

In testimony that I claim the foregoing as 35 my invention I have signed it this 26th day of January, 1880.

EGERTON A. BLISS.
